LOOM

Horace H. Burdett, Hopedale, Mass., assignor to
Draper Corporation, Hopedale, Mass., a corpora-
tion of Maine

Application August 20, 1937, Serial No. 160,117

1 Claim. (Cl. 139—162)

The present invention pertains to fly shuttle looms, and more particularly to picker checks for such looms.

Looms of the type to which my invention applies include a forwardly and rearwardly reciprocating lay having a shuttle box, a picker actuated to pick a shuttle out of the shuttle box, and picker check means for checking the picker and shuttle when the latter returns to the shuttle box. Usually, the picker is fixed to or engaged by a picker stick and the check means acts on such picker stick. In prior looms of this type, the construction is such that the picker, picker stick, and check element are stationary (except for forward movement with the lay) when the returning shuttle strikes the picker, and the shuttle cannot fully enter the shuttle box unless it possesses appreciably more kinetic energy than is necessary to set the picker, picker stick, and check element in motion.

I propose to provide a fly shuttle loom having a reciprocating lay, shuttle box, shuttle, and picker as aforesaid, a picker check element for checking outward movement of the picker and shuttle when the latter enters the shuttle box, and means, other than the shuttle, for imparting outward motion to the picker and check element just before the picker is engaged by the boxing shuttle, whereby the shuttle is not required to possess as much kinetic energy as in the aforesaid prior construction.

The foregoing and other objects of the invention are accomplished in the construction illustrated on the accompanying drawings, of which: Fig. 1 is a perspective view of one side of a loom having the preferred embodiment of my invention applied thereto;

Fig. 2 is a side view of the same;

Fig. 3 is a plan view, partly in section, showing the mechanism of Fig. 1 with the lay forward; and

Fig. 4 is a view similar to Fig. 3 but showing the lay in its extreme rearward position.

The drawings show only part of a loom having my invention applied thereto, parts and mechanisms not shown being of usual construction well known in the art. It is noted, however, that the complete loom includes a pick motion and picker stick check at each side of the loom and while both such picker stick checks may be constructed in accordance with my invention only one of them is shown and described.

The loom frame includes a right hand loom side 1. The lay includes a lay beam 2 which extends widthwise of the loom and is reciprocated to-

ward and from the front of the loom in the usual manner. A shuttle box is provided at each side of the loom, of which the drawings show the right hand shuttle box 3 carried by the lay. A shuttle 4 is adapted to be picked back and forth along the lay, into and out of the shuttle boxes. The shuttle is thus picked by suitable pickers such as the picker 5 which is fixed on the upper end of a picker stick 6. The picker stick has a shoe 7 which rocks on a parallel 8. The picker stick rocks or moves in an inward direction, which is toward the center of the loom to pick the shuttle out of the shuttle box 3 toward the other side of the loom. Means for imparting inward or picking movement to the picker stick and picker may include a pick arm 9 and lug strap 10.

The parts as thus far described in detail are of usual construction and are of the present invention only in that they may cooperate with other parts, hereinafter described, to form a complete operative combination. A similar or any suitable picking motion may be provided at the other side of the loom. The shuttle 4 is picked out of the shuttle box 3 as the lay is moving rearwardly and arrives at the other side of the loom as the lay moves forwardly. In the case of a single shuttle loom, the shuttle 4 will return to the shuttle box 3 on the next succeeding forward beat of the lay, as is well known in the art. The picker stick is commonly positioned so that the returning shuttle strikes the picker when the shuttle is only partly entered into the shuttle box. Thus, the picker and picker stick are moved outwardly by the returning shuttle and picker check means are provided for checking the picker and picker stick and assisting in checking the shuttle.

The preferred embodiment of the invention includes a novel picker check means constructed and arranged to position the picker 5 and picker stick 6 much farther inwardly of the loom, prior to the boxing of the returning shuttle, than has been the practice heretofore. Such check means is further arranged to set the picker stick and movable parts of the check into motion in an outward direction just before the returning shuttle engages the picker.

In the said preferred embodiment, a picker stick check element 11 is arranged to be moved outwardly of the loom by the picker stick 6 in checking the picker stick and shuttle. To this end the element 11 may comprise an arm 13 which is pivotally mounted on a stud 12 and which has a free end extending forwardly and engaging the outer side of the picker stick 6. The 55

stud 12 is fixed in a bracket 14 which is bolted to the lay and extends rearwardly therefrom. A conventional form of heel spring 15 (Fig. 1) is connected to the picker stick by a strap 16. The heel spring and strap comprise means for yieldingly urging the picker stick outwardly against the free end of the arm 13.

The element 11 is extended rearwardly beyond the stud 12 and the rearwardly extending portion is provided with an arcuate slot 17. A cam follower member 18 is pivotally supported on the stud 12 below the element 11 and includes a downwardly extending cam follower 19. A rod 20 is fixed in the member 18 and extends upwardly through the slot 17. A coiled compression spring 21 on the rod 20 pushes the element 11 downwardly into frictional engagement with the upper face of the member 18. The cam follower is thus frictionally connected with the arm 13. The frictional connection is sufficiently strong to cause the arm 13 to be moved by the cam follower but will permit the arm to move relative to the cam follower as will hereinafter appear.

The arm 13 is moved by cam means, preferably consisting of a stationary cam 22 which has a cam track in which the follower 19 runs. The cam 22 is fixed to a bracket 23 which is carried by the loom side 1. The front portion 24 of the cam track extends forwardly and rearwardly of the loom while the back portion 25 thereof curves rearwardly and outwardly. Since the lay, check element 11 and cam follower member 18 reciprocate forwardly and rearwardly while the cam 22 remains stationary, the cam will cause the arm 13 to swing inwardly as the lay moves back, and outwardly as the lay moves forwardly.

In the embodiment shown, the arm 13 swings inwardly and outwardly each time the lay makes one complete cycle of movement, but is called upon to perform its checking function only upon alternate forward beats of the lay. Starting with the lay at its extreme forward position and with the shuttle 4 in the shuttle box 3, the lay then moves rearwardly and the picking means 9, 10 operates to move the picker stick 6 inwardly when the lay is about half way back. Simultaneously with the inward movement of the picker stick, and as the lay continues its rearward movement, cam 22 moves the cam follower 19 outwardly, thereby swinging the arm 13 inwardly with the picker stick. Then, as the lay moves forwardly the arm 13 will move outwardly and the spring means 15, 16 causes the picker stick to follow the arm, the shuttle being at the other side of the loom.

When the lay next moves rearwardly the shuttle 4 will still be absent from the shuttle box 3 and the picking means 9, 10 will not operate. The cam 22 will, however, swing the arm 13 inwardly, and the latter will move the picker stick, as the lay moves rearwardly. This places the arm and picker stick substantially at their innermost positions. The shuttle 4 is then due to return to the shuttle box 3 shortly after the lay

starts its next forward movement. At the beginning of such forward movement of the lay the cam 22 imparts outward motion to the arm 13, and the spring means 15, 16 causes the picker stick to move outwardly with the arm. 5 Thus, the picker 5, picker stick 6, and arm 13 are set in motion in an outward direction just prior to or in advance of the time when the returning shuttle engages the picker 5. The initial speed of these parts is preferably equal to 10 or slightly less than the speed of the returning shuttle, and is thereafter reduced, to check the picker stick and shuttle.

The setting of the picker stick 6 and picker stick check arm 13 in motion in an outward 15 direction prior to the time of engagement of the returning shuttle with the picker relieves the shuttle of the burden of setting these parts in motion. The results are a more uniform and reliable checking of the shuttle and picker stick, 20 a reduction in the possibility of "bang-off" due to a weak pick, and some saving in the power required to pick the shuttle across the loom and into the shuttle box.

It may happen that, because of improper setting of the pick motion or for other reasons, the shuttle will enter the shuttle box at much greater velocity than the velocity of the outward movement of the picker permitted by the cam 22. In this case, the frictional connection between the 30 cam follower member 18 and the arm 13 will yield, to permit the picker stick 6 and arm 13 to be moved by the picker stick independently of the cam follower. Outward movement of the arm 13 is limited by a stop 26 which is formed 35 integrally with the bracket 14 and projects downwardly beside the rearward extension on the arm as shown more clearly on Fig. 3. After the arm 13 has been moved outwardly to the position determined by the stop 26, but on the same 40 forward beat of the lay, the cam 22 will continue to swing the cam follower 19 inwardly, thereby restoring proper angular relation between the cam follower member 18 and the arm. An adjusting screw 27 carried by the member 18 45 engages the rearward extension on check element 11 to adjust the check element relative to the cam 22.

Having fully disclosed the preferred embodiment of my invention, I claim:

In a fly shuttle loom, a forwardly and rearwardly reciprocating lay, a picker stick, means imparting inward picking movement to said picker stick as the lay moves rearwardly, a picker stick check comprising a pivoted arm having a 55 free end engaging the outer side of said picker stick, a cam follower, means frictionally connecting said arm with said cam follower, and cam means engaging said cam follower for swinging said arm inwardly as the lay moves back and 60 outwardly as the lay moves forwardly, said frictional connection yielding to permit said arm to be moved outwardly by said picker stick.

HORACE H. BURDETT.
